UNITED STATES PATENT OFFICE

151,462

DESIGN FOR A DISPLAY STAND FOR WATCH BRACELETS AND BANDS

Charles A. Mealy, East Orange, N. J., assignor to
Forstner Chain Corporation, a corporation of
New Jersey

Application October 4, 1946, Serial No. 133,747

Term of patent 3½ years

(Cl. D80—9)

To all whom it may concern:

Be it known that I, Charles A. Mealy, a citizen of the United States, residing at East Orange, in the county of Essex and State of New Jersey, have invented a new, original, and ornamental Design for a Display Stand for Watch Bracelets and Bands, of which the following is a specification, reference being had to the accompanying drawing, constituting a part thereof:

Fig. 1 is a front elevational view of a display stand for watch bracelets and bands, showing my new design; and

Fig. 2 is a side elevation thereof.

I claim:

The ornamental design for a display stand for

watch bracelets and bands, substantially as shown.

CHARLES A. MEALY.
